(57) **CLAIM**

The ornamental design for a wearable electronic device, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a wearable electronic device, showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof;

FIG. 8 is another front perspective view thereof;

FIG. 9 is an enlarged view of a portion defined by lines 9-9 shown in FIG. 1; and,

FIG. 10 is an enlarged view of a portion defined by lines 10-10 shown in FIG. 3.

The dashed broken lines in the drawings illustrate portions of the wearable electronic device that form no part of the claimed design. The dot-dot-dash broken lines in FIGS. 1, 3, 9 and 10 are included to show a partially enlarged view only and form no part of the claimed design.
